UNITED STATES PATENT OFFICE.

WILLIAM H. MARSHALL, OF EVERETT, ASSIGNOR OF ONE-HALF TO EDGAR W. ANTHONY, OF BROOKLINE, MASSACHUSETTS.

WATER-HEATER.

SPECIFICATION forming part of Letters Patent No. 511,630, dated December 26, 1893.

Application filed July 11, 1892, Serial No. 439,556. (No model.)

To all whom it may concern:

Be it known that I, WILLIAM HARRY MARSHALL, of Everett, in the county of Suffolk and State of Massachusetts, have invented a new Improvement in Water-Heaters; and I do hereby declare the following, when taken in connection with accompanying drawing and letters of reference marked thereon, to be a full, clear, and exact description of the same, and which said drawing constitutes part of this specification, and represents a vertical central section of the boiler complete.

This invention relates to an improvement in water-heating apparatus, adapted to the employment of gas as fuel, the invention being designed for boilers of the smaller class, such as used for soda-fountains and other places where but a small quantity of water is required to be heated, and the heat maintained as the water is drawn therefrom, the object of the invention being to automatically regulate the flow of gas, and so as to maintain substantially a constant temperature of the water, and the invention consists in the construction of the apparatus as hereinafter described and particularly recited in the claims.

A, represents the body of the boiler, which may be made of any suitable material, and of a size according to the capacity required. It is tightly closed so as to prevent the escape of steam or water except through apertures provided for the purpose.

B, represents the top of the boiler, which is secured to the boiler proper, so as to make the boiler secure and tight.

In the upper part of the boiler is a receiving chamber C, which opens through a tube D, into the boiler near its bottom.

E, represents the inlet water pipe, which leads into the chamber C. As here represented the pipe E extends through the top or cover of the boiler, and so that water coming into the boiler will first flow through the chamber C, and thence find its way to the bottom of the boiler through the tube D.

F, represents the gas-burner, which as here represented is the common Bunsen burner. Gas is led to the burner over the top of the boiler through the tubes G, as represented.

Over the receiving chamber C, is a cham-

ber H. This chamber is formed by a central recess in the top B, of the boiler. The recess is of circular shape, and is constructed with an internal annular shoulder I, at the top of the chamber H; the walls and bottom of the recess forming the chamber H, are cast integral with the cover. The bottom of the chamber H, forms a close partition between it and the receiving chamber C, below, and so that the bottom of the chamber H, is exposed in the chamber C. In the top of the chamber H, a flexible diaphragm J, is arranged; this is best made from thin elastic metal, and is firmly secured to the walls of the chamber H, at the top of the chamber, as by soldering the edge of the diaphragm around the edges of the top of the chamber, so that it is firm in its position, yet adapted to yield up and down; at the same time it perfectly closes the top of the chamber, so that air can neither enter nor escape from that chamber. The chamber H may be filled with air, or other fluid than air which is capable of expansion and contraction under variations of temperature. 75

In the gas pipe which passes over the boiler a valve is arranged to automatically regulate the flow of gas. As here represented this valve consists of a shell K, having a vertically moving valve L, arranged therein, adapted to move up and down, and as here represented the valve closes by an upward movement. The spindle M, of the valve extends upward through a guide N, in the shell, and into the space above the valve the inlet gas pipe O, leads, so that the flow of gas will be into the shell above the valve L. The outlet passage P, leads from below the valve seat into the supply-pipe G, as clearly shown. A spindle Q, extends downward from the valve 85 through the shell, and to pack the spindle so as to prevent the escape of gas a flexible diaphragm R, is introduced below the valve-seat in connection with the valve spindle, the diaphragm extending to the shell, and there secured by its edges, a common and well known packing device. The valve is held normally open by means of a spring S, arranged in the shell above the valve-spindle M, one end of the spring resting upon a cap T, which sets 90 on the end of the spindle M, as shown, and in the shell above is an adjusting-screw N, by

which the pressure of the spring may be varied, as occasion requires, and this projection of the shell which forms the spring-chamber is closed at its upper end by a cap V, so as 5 to cover and prevent tampering with the adjusting-screw U. By this arrangement and location of the spring it is removed from the source of heat as far as permitted, so that the influence of the heat thereon is reduced to a 10 minimum, and hence it will counteract the action of the diaphragm as little as possible.

Onto the shoulder I, within the recess in the top of the boiler, a disk W, is secured, through which is an opening X, onto the diaphragm J. The valve is secured to the disk. Over this opening the base Y, of the valve sets onto the top of a projection on the disk, through which the opening X, is formed, and a flanged nut Z, screwed onto the projection 15 from the disk W secures the two parts together, this being a common and well known joint. The shell of the valve is made as a part of the base Y, and is connected thereto by bars a, more or less in number, but preferably so as to leave an open space between 20 the base and the body of the shell.

Through the base Y, of the valve-shell is a vertical step b, the lower end of which rests directly upon the diaphragm J, and so as to 25 be supported thereby; the spindle Q, of the valve screws into the upper end of the step b, and so that this step becomes practically a part of the valve-stem, but the screw connection permits an adjustment between the step 30 and the valve, so that the relation of the valve to its seat may be changed without affecting the normal position of the diaphragm, that is to say, the opening of the valve may be increased by screwing the valve-spindle Q, into 35 the step to a greater extent, or decreased by a reverse adjustment, but when adjusted, and without influence from the chamber H, the normal position of the valve is, open to a certain extent so as to permit the flow of gas, it 40 being understood that when the flow of gas is required to be cut off entirely, the common supply cock arranged in the pipe O, not shown, is employed.

In operation the boiler is filled with water, 45 and gas being turned on will flow through the normally open valve to the burner, and there lighted, the flame coming upon the bottom of the boiler will heat the water, and as the temperature rises within the boiler, heat will be imparted to the chamber H, to expand the air, or other fluid within that chamber, and such expansion of the fluid will cause the diaphragm J, to rise and impart a corresponding rising movement to the valve, and which will 50 accordingly reduce the flow of gas to the burner, and consequently reduce the heat which is applied to the boiler. As the valve rises the spring S, will be compressed until the valve is completely closed. Such complete 55 closing of the valve would cut off the supply of gas, and the flame would be extinguished, but such entire extinguishment of the flame

is not desirable, as it must continue lighted in order to work satisfactorily. To permit a flow of gas sufficient to maintain a small flame 70 at the burner, a leak opening d, is arranged from the gas supply pipe into the valve-chamber below the valve-seat, and so that while the valve may be closed, there will still a small amount of gas pass through the leak 75 d, and thence to the burner, sufficient to maintain a substantially non-effective flame. The leak is regulated by a screw e, which is adapted to increase or diminish the extent 80 of opening of the leak, as may be required. This is a common device in connection with gas burners. As soon as the heat is reduced below a predetermined degree of temperature, the fluid in the chamber H, will contract, and the diaphragm will fall and permit the valve 85 to open under the action of its spring S to permit an increased flow of gas, and consequently increase the flame. The incoming water, which is of a low temperature, entering as it does the chamber C, directly below the chamber H, will operate to quickly 90 cool or reduce the temperature upon the fluid in the chamber H, so that as water is drawn from the boiler, the inflow of water operates quickly to increase the flame to raise the temperature of the water naturally reduced by 95 the inflowing of fresh water. Under this arrangement substantially a constant temperature of the water may be maintained, the degree adjusted by the resistance which is offered to the closing of the valve.

To create a rapid circulation of the water through the chamber C, so that not only may the cold water which comes therein operate quickly upon the chamber H, but that the 105 water in the chamber may be heated quickly so as to communicate its heat to the chamber H, openings f, are made in the tube D, near its upper end. The result of this is that whereas the cold water will flow directly down through the tube D, the circulation thus produced will cause the heated water to flow inward through the openings F, into the chamber, the circulation being down through the tube, up outside the tube through the openings f, into 110 the chamber C. The boiler is provided with a suitable outlet pipe g, by which the water may be drawn from the boiler.

While it is preferred to employ the chamber C, as the best means through which to operate upon the regulating chamber H, the chamber C, may be omitted, in which case the water may be directed from the incoming tube onto the bottom of the regulating chamber, so that the inflow will be first brought 120 upon that chamber to reduce the temperature therein. The tube D, which leads from the bottom of the chamber C, directly to the bottom of the boiler, may be omitted, the chamber serving as the means for directing the incoming water onto the bottom of the regulating chamber H, and so that the natural circulation within the boiler will take the 125 fresh water from the chamber C, downward, 130

or the water may be led directly to the bottom of the boiler, as indicated in broken lines, without this instant effect upon the regulating chamber for its operation, in that case 5 depending upon the natural circulation of the water within the boiler.

I claim—

1. In a water heater, the combination of a boiler, a gas-burner below the boiler, a gas- 10 supply pipe leading to said burner, a water receiving chamber located within and opening into the boiler, a water supply pipe opening into said receiving chamber, a regulating chamber arranged over the receiving-chamber, 15 a flexible diaphragm across the top of said regulating chamber the bottom of which latter forms the top of the said receiving chamber, a valve in the gas supply pipe, the spindle of which is supported by said diaphragm, and the boiler provided with an outlet, substantially as and for the purpose set forth.

2. The combination of a boiler A, having a top B, constructed with a recess forming the 25 walls and bottom of a chamber H integral with said top, a diaphragm J, secured to the walls of said chamber, and so as to form the top thereof, a gas-burner below the boiler, a pipe adapted to lead gas to said burner, and 30 passing over said diaphragm, a valve in said gas supply pipe arranged over said diaphragm, the said valve supported upon said diaphragm in a normally open position, the boiler provided with water inlet and a water outlet, 35 substantially as and for the purpose described.

3. The combination of a boiler having a recess in its top forming a chamber H, a chamber C, within the boiler, and surrounding the 40 bottom of said chamber H, an inlet pipe leading into said chamber C, a diaphragm J, across said chamber H, and so as to form the upper side thereof, the said chamber C, having an opening into the boiler, a gas-burner 45 below the boiler, a pipe leading to said gas burner for the supply of gas, a valve in said

gas supply pipe over the said diaphragm, the said valve supported upon said diaphragm in a normally open position, and the boiler provided with an outlet, substantially as de- 50

4. The combination of a boiler constructed with a chamber H, in its top, a chamber C, within the boiler and surrounding the bottom of the said chamber H, an inlet water supply 55 pipe opening into said chamber C, a pipe within the boiler opening from the said chamber C downward toward the bottom of the boiler, a diaphragm forming the upper side of the said chamber H, a gas-burner below 60 the boiler, a gas pipe leading to said burner and passing over said diaphragm, the valve in said gas pipe above the diaphragm, the valve supported upon said diaphragm and normally in an open position, the boiler also 65 provided with an outlet, substantially as described.

5. The combination of a boiler, a gas burner below said boiler, a gas-supply pipe leading to said burner and passing over said boiler, 70 the boiler constructed with a regulating chamber, a valve in the gas-pipe supported by the said regulating-chamber normally in an open position, a water-receiving chamber within the boiler and surrounding the bottom 75 of said regulating chamber, a water-supply pipe opening into said receiving-chamber, a pipe leading from the bottom of said receiving-chamber downward toward the bottom of the boiler, and constructed with openings 80 through into the boiler near the bottom of said receiving chamber, the boiler also provided with an outlet, substantially as described.

In testimony whereof I have signed this 85 specification in the presence of two subscribing witnesses.

WILLIAM H. MARSHALL.
